BURTON S. AIKMAN, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

PUMP AND PUMPING SYSTEM.

1,255,972.

Specification of Letters Patent. Patented Feb. 12, 1918.

Application filed March 31, 1917. Serial No. 158,808.

To all whom it may concern:

Be it known that I, BURTON S. AIKMAN, a citizen of the United States, resident of Milwaukee, in the county of Milwaukee and 5 State of Wisconsin, have invented a certain new and useful Improvement in Pumps and Pumping Systems, of which the following is a full, clear, concise, and exact description, reference being had to the accompanying 10 drawings, forming a part of this specification.

My invention relates to pumps and pumping systems and contemplates an improved apparatus which may be employed as an isolated plant for furnishing water to a residence or an industrial establishment from a nearby source, such as a well.

It is the purpose of my invention to provide an improved system which supplies 20 water "fresh from the well," that is without the intervention of a storage or reserve tank, and which will be under "faucet control" by which I mean that the flow of water is controlled by the acts of opening and closing 25 the faucets which form the supply outlets of the system.

To supply water fresh from the well and to maintain the flow of water under faucet control is matter of prior art. The apparatus and systems heretofore known and used were, however, subject to inherent difficulties, due to the fact that their mode of operation required complexities such as alternately-operating chambers, valves operated by marginal differences in pressure or by time-element devices, and to the fact that the pneumatic control employed led to frequent misoperations such as are commonly called "blow-overs" where the system becomes cleared of water and the compressed air, employed as an operating medium, is wasted.

According to my invention, there is provided a single water-chamber alternately subject to air pressure and relieved therefrom, the alternations being secured by the actuations of valve mechanisms which, in turn, are directly and mechanically dependent upon the rise and fall of the water in the chamber. It will be understood that the system is constantly under pressure and it is therefore a further object of my invention to provide an apparatus which will be as free from leaks as possible, which operates with 55 a minimum consumption of air and which

operates reliably and positively. The last mentioned characteristic is due to the direct relation of the valve mechanism to the water levels, whereby the movement of the valve is dependent upon the physical change which 60 requires such movement, and I provide means for causing sudden actuations of the valve mechanism notwithstanding the fact that the rise and fall of the water in the chamber is comparatively gradual. 65

My invention is illustrated in the accompanying drawings, in which—

Figure 1 is a more or less diagrammatic view illustrating the system as a whole;

Fig. 2 is a plan view of the pump; 70

Fig. 3 is a vertical axial sectional view taken on the plane of the line 3—3 of Fig. 2 and looking in the direction indicated by the arrows;

Fig. 4 is a vertical, axial sectional view 75 taken on the plane of the line 4—4 of Fig. 2 and looking in the direction indicated by the arrows;

Fig. 5 is a sectional view taken on the plane of the line 5—5 of Fig. 3 and looking 80 in the direction indicated by the arrows;

Fig. 6 is a detail view of the controlling valve; and Fig. 7 is an enlarged fragmentary sectional view of the valve shown in Fig. 3. 85

Referring first to Fig. 1, which, as before stated, is diagrammatic, it will be seen that the well curbing is illustrated at 8, the water-level being indicated at 9. The pump structure, which I have indicated broadly by the reference character 10, is disposed in the well at a suitable distance below the water-level therein, as will be described. The pump structure has leading therefrom three pipes, an air-pressure pipe 11, an exhaust pipe 12, and a water-discharge pipe 13. The air-pressure pipe 11 is connected with a compressed-air tank 14, in which air is compressed by means of a compressor 15, operated, for instance, by an electric motor 16. 100 It will be clear to those skilled in the art that the compressor 15 may be operated by any suitable means, such as a gas engine or steam engine, and if desired means may be provided for automatically starting and stopping 105 the prime mover dependent upon the fall and rise of pressure in the tank 14. In the pipe 11 the cut-off valve 11^a, air strainer 11^b, reducing valve 11^c, gage 11^d, and drain cock 11^e are provided.

2
 The water discharge pipe 13 leads to various branch pipes 17 and 18, each of which, in turn, leads to an outlet faucet 19. By means of a pipe 20, the discharge pipe 13 is connected with a chamber 21, closed except for the entry pipe 20, for a purpose which will be pointed out presently.

It will now be understood that this system represents an isolated plant for installation in a residence, for instance. The water discharge pipe leads from the well, conveniently nearby, to the distribution pipe in the building, and the compressor, motor, compressed air tank and chamber are suitably housed in any convenient way.

As before pointed out, pressure is constantly maintained upon the system. It is therefore necessary to maintain a certain pressure between predetermined minimum and maximum limits in the compressed-air tank 14, this being done by the proper starting and stopping of the compressor 15, either manually or automatically. It has been my experience that, a proper compressed air tank being provided, it is necessary, in employing a distribution system for an ordinary residence, for instance, merely to operate the compressor intermittently, say every two or three days, for a short time, in order to keep the pressure in the compressed air tank within the desired limit.

It will appear as this description proceeds that, with the pressure properly maintained upon the system, everything is at rest so long as all the outlet faucets of the system are closed, but as soon as one of them is opened the pumping mechanism will operate to maintain continuous the flow which immediately commences. When the faucet is again closed the apparatus comes to rest and it will appear that the feed has been direct from the well with the proper pressure to distribute it to whatever points desired.

I refer now to Figs. 2 to 6, inclusive, to describe the pumping mechanism. A head member 22 and a base member 23, both of circular form, are joined by a cylindrical housing 24, which forms a water chamber 25. As illustrated in Fig. 4, the head member 22 and the base member 23 are tied together by means of two pipes 26-26 which thread into downward extensions from the head member 22 and which set in sockets 27-27 in the base member 23. Cap screws 28-28 which, as shown, pass through the wall of the foot member 23, firmly hold the base member 23 in place and clamp the housing 24 between the base member and the head member to form a water tight and air tight compartment which serves as the cylinder of the pump.

The base member 23 is provided on its under side with a central extension 30 to 65 which a nut 31 is screw threaded, a conical

screen 32 being clamped between the nut 31 and the extension as illustrated. The base member 23 is provided with two water inlet openings 33-33 each of which is controlled by a lift valve 34 mounted to reciprocate in a bracket 35 on the upper side of the base member 23 and provided with a spring 36 tending to hold it in closed position thus forming check valves. The water which comes into the water chamber by way of the opening 33-33 is, as will be described later, forced from the chamber by way of the openings 37-37 in the lower ends of the pipes 26-26, the water passing upwardly through the pipes 26-26, as will be described.

The head member 22 is provided with the exhaust or atmosphere passage 47, the compressed air inlet passageways 48 and 49, the primary water chambers 50-50 with which the pipes 26-26 are connected, and a secondary water chamber 51. These passageways and chambers are isolated from each other, as will be described, the atmosphere or exhaust passageway being connected with the pipe 12, the compressed air inlet passageway 48 being connected with the pipe 11 and the secondary water chamber 51 being connected with the discharge pipe 13.

Referring now to the exhaust outlet or atmosphere passageway 47, it will be seen that it is so fashioned as to lead to the axial opening 52 in the head 22, a valve seat 53 surrounding this opening. A lift valve 54 having a compressible face 55 co-operates with the valve seat 53 to open and close the opening 52, the valve 54 being mounted upon a stem 56 for vertical movement. The stem 56 is provided with a shoulder 57 to which I shall refer again later, and with an enlargement 58 which rides in a sleeve 59 set axially in the head 22 and disposed concentrically in the opening 52. A helical spring 60 is confined in the sleeve 59 between the enlargement 58 and the face of the valve 54. The compressed air inlet passageway 48 is connected by a port 61 which has a valve seat 62 surrounding the upper end thereof, this valve seat co-operating with a valve 63 having a compressible face 64. The valve 63 is mounted on an auxiliary stem 56' which passes through the opening 61 and is arranged to be engaged by the enlargement 58. The valve 63 is guided in a pocket 68 axially in the top of the head 22, this pocket being closed by a plug 69. The valve 63 is provided with lands 70 in order to balance the pressure on opposite sides of the valve when it is in open position, a spring 71 being disposed between the plug 69 on the valve and tending to move the valve downwardly.

Secured to the under side of the head 22 is a cylinder and valve structure. This structure provides a diaphragm chamber or

cylinder 73 which is closed at the top by the diaphragm 74, the central part of this diaphragm being clamped between the two plates 75—75 which in turn are clamped 5 against shoulder 76 on the stem 56 by means of a clamping nut 77. This stem 56 extends down and is guided in a spider 78. A spring 78' is disposed between the top plate 75 and the valve 54.

10 The diaphragm chamber 73 is provided with two ports, the compressed air port 79 and the exhaust port 80. The compressed air port 79 is connected with the compressed air passageway 48 by means of the passageway 81, cored in the diaphragm chamber casing 72 and in the head 22, and the exhaust port 80 is connected with the exhaust passageway 47 by means of the passageway 82, cored in the diaphragm chamber casing 72 and the head 22, as clearly illustrated in Fig. 3.

15 The valve mechanism which controls the two ports 79 and 80 will now be described. It will be seen that these two ports are co-25 axial and that they are transversely opposite each other. The port 79 which is of relatively small diameter is formed in a removable member 83 seated in the screw plug 84 which threads into the lower part 30 of the cylinder structure member 72. This screw plug 84 is provided with a suitable axial opening and radial openings to put the port 79 in communication with the compressed air passageway 81. The exhaust 35 port 80 is formed or defined by two concentric tubes 85 and 86 of which the first is mounted in the front wall of the exhaust passageway 82 and the other 86 is mounted in the rear wall of that passageway. The 40 inner concentric tube 86 forms a guide for the stem 87 of a double faced valve member 88, which has a yielding face 89 adapted to cover the port 80 and another yielding face 90 adapted to close the port 79. The diaphragm frame member 72 is provided with a flange 91 surrounding the tube 86 and stem 87, a yielding diaphragm 92 being clamped to the flange 91 by means of the ring 93.

45 Supported from the bracket 94 which is clamped upon the pipes 26 is a cylinder 95 closed, except for the openings 96 along the upper end of the cylinder, and except for the open bottom. Toward the lower end of the cylinder 95 it is internally provided with a ring 97 which provides a valve seat 98 adapted to be engaged by the ball float valve 99. This ball float valve 99 is held in the lower end of the chamber by the bracket member 35 which guides the check valve 34. 50 The lower end of the cylinder 95 is secured by a bracket 113 clamped on the vertical pipe 26. A bracket 109 extends from the clamping ring 93 and supports a pivot for the bell crank lever 101 at 102. The upper 55 arm of the bell crank lever connects with

a bracket which is threaded upon the outer end of the valve stem 87. This valve stem is provided with a shoulder between which and the bracket 103 a pair of plates 114 are clamped upon opposite sides of the diaphragm 92. The lower arm of the bell crank lever extends over the cylinder 95 and a water weight or float 104 is connected by means of a link 115 to the lower arm of the bell crank lever 101. The lower end of the 75 water weight or float is provided with a stem 106 which extends down into a guiding sleeve 107 carried from the ring 97 by means of the spider 108. The stem 106 projects through the head 116 that closes the lower 80 end of the water weight and this stem is connected on its inner side with the balancing spring 117 which extends up through the inside of the water weight and is hung from a pin 118 fastened upon the diaphragm 85 chamber structure 72.

The water chambers 50—50 are provided with the outlet passageways 109—109 each of which is controlled by a check valve 110 between which and a corresponding plug 111 90 a spring 112 is disposed. As will be described, the water is forced from the chambers 50—50 into the secondary water chamber 51 passing through these valves and from the secondary chamber 51 the water is forced 95 on to the distributing system.

95 The controlling valve 88 which controls the pressure existing below the diaphragm is removable through the opening in the diaphragm chamber structure that is normally 100 closed by the plug 84. For this purpose it is provided with the slot 119 to permit the valve to be disconnected as by means of a screw driver. It is thus apparent that the valve may be readily renewed or inspected 105 when desired.

The operation of the device is as follows:

Assume that a stroke has just been completed and that the water is rising to fill the pump cylinder when the parts are in 110 the condition shown in Fig. 3. Due to the head of water in the well, the check valves 34 are lifted and water flows into the cylinder 25. The main diaphragm is in its lower position as indicated in Fig. 3 and the exhaust valve 54 is open and the compressed air admission valve 63 is closed. The air in the pump cylinder 25 escapes through the screens 120 which cover the apertures in the screen supporting ring 121 and passes 115 through the exhaust ports 52 into the exhaust chamber 47 and out by way of the pipe 12. The water weight 104 is in its lower position and it holds the valve 88 over the compressed air admission port 79 120 and uncovers the exhaust port 80 for the diaphragm operating cylinder. As the water rises in the cylinder 25 the first operation is to raise the float valve 99 and to bring it against its seat 98 thereby closing off the 130

bottom of the chamber 95. The water then rises until it reaches the opening 96 in the cylinder 95 and as the water rises farther it quickly fills the cylinder 95 and the water weight 104 loses enough weight by the supporting action of the water in the cylinder 95 to permit the spring 117 to raise this water weight quickly to its uppermost position. This movement of the water weight 104 operates the bellcrank lever 101 to throw the valve body 88 to the right, as viewed in Fig. 3, opening the compressed air admission port 79 for the diaphragm cylinder and closing the exhaust port 80 for the same. The pressure within the diaphragm cylinder also aids in holding the valve 88 over the exhaust port 80 because of the increased area upon which the compressed air is effective. The differential area of this valve is effective in producing a snap action which is desirable. As the port 79 is opened, the cylinder below the diaphragm is filled with air under pressure and the diaphragm rises. The first action of the diaphragm in rising 25 is to bring the exhaust valve 54 upon its seat to cover the exhaust port 52. Further movement of the diaphragm compresses the spring 78 and moves the stem 56 independently of the valve 54 to engage the stem 56' and to raise the compressed air admission valve 63. As the admission valve 63 is operated compressed air will be admitted to the cylinder above the water therein and the water is forced through the openings 37 in the pipes 26 up through the pipes 26 through the primary water chamber 50, past the check valves 110 through the secondary water spaces 51 and out by way of the pipe 13. The checkvalves 34 are held closed 40 by the pressure of the water against the top thereof. As the level of the water in the cylinder 23 falls, it does not affect the level of the water in the water weight 95 as the bottom of this chamber is still held closed by the float valve 99. When, however, the level of the water has dropped to such a point that the float valve 99 drops away from its seat 98, the water in the water weight chamber 95 escapes suddenly 45 and the water weight losing the supporting effect of the water in the chamber 95, drops quickly shifting the valves 88 from the port 80 to the port 79 cutting off the supply of compressed air to the diaphragm cylinder 50 and opening the exhaust valve to said cylinder.

So long as water is moving out of the pump the pressure on the upper side of the diaphragm does not equal that upon the lower side and the admission valve 63 is open. In case the pressures become equalized as when the faucets are all closed, the valve 63 may close. As soon as the faucets are opened the pressure in the pump drops 60 due to the expansion of the air and expul-

sion of the water. As the compressed air has access to both sides of the diaphragm during the expulsion of the water, release of the pressure on the lower side of the diaphragm by shifting of the valve 88 causes a quick movement of the diaphragm downward due to the pressure of the air within the pump above the same and the first consequence of downward movement of the diaphragm is to lower the stem 56 first seating the compressed air admission valve 63 then compressing the spring 60 between the enlargement 58 and the exhaust valve 54 until the shoulder 57 strikes the top of the exhaust valve 54 moving the same off of its seat. This opens the exhaust port 52 and the spring 60 is then able to expand and move the exhaust valve 54 farther downward clearing the exhaust port 52 sufficiently to prevent it being thrown against this port by the outrush of air in the cylinder. As the compressed air valve 63 is closed and the exhaust valve 54 is opened, the pressure in the pump cylinder 24 quickly falls and the head of water in the well 90 forces water past the check valve 34 filling the pump. Under the head of the water in the well an immediate inrush of water from the well follows. The valves 34—34 open to permit this entry of water and as the water rises in the chamber 25 the float valve 99 is raised to its seat 98 to close off the cylinder 95 above that point. Thus, although the water rises farther in the water chamber 25, it does not rise within the cylinder 95 beyond the valve and there is no effect upon the water float until the water in the chamber 25 has reached the plane of the bottom of the opening 96, after which it pours into the cylinder 95 quickly and 105 raises the float or water weight to shift the valve 88.

The speed with which the chamber 25 fills to the upper level of course depends upon the size of the inlet passageways and the head 110 of the water in the well. I have made experiments which show that with a structure built substantially along the lines of that illustrated in the drawings and substantially those proportions submerged about ten feet 115 below the level of water in the well a period of about $1\frac{1}{2}$ seconds is required for the filling operation. If the capacity of the discharge and distributing pipe is great enough this momentary cessation of pressure will be 120 hardly perceptible at the faucet, particularly since the expulsion period, assuming one or more faucets to be opened for a considerable length of time, consumes practically all the time. However, in order that the gap in the flow may be properly filled in I provide the air chamber 21 to which the pipe 20 delivers from the discharge pipe 13. Obviously, when the water in the discharge pipe 13 is under pressure, as it is practically all of 130

the time, a certain amount of water is forced up into the chamber 21. This action compresses the air in the chamber and forms a cushion which is maintained so long as the pressure is not relieved. As soon as the pressure is relieved, however, by the cessation of pressure in the pump with a faucet opened, the air is given opportunity to expand and in doing so forces out the water which has been trapped therein and provides a flow from the faucet during the refilling period of the pump. This chamber 21 will, of course, be distinguished from a storage tank, since all that it does is to smooth out the variations in pressure in the system.

The flexible diaphragm 92 to which the stem 87 is secured prevents the entry of sand, dirt or water between the stem 87 and the sleeve 86.

20 Where the general combination of parts herein described and illustrated is claimed in copending application, Serial No. 52,808, the claims in the present application are directed to the specific improvement in the 25 controlling valve. I do not intend to be limited to the precise construction shown and described as the invention may appear in other forms.

I claim:

30 1. In a pump, the combination of a diaphragm, a cylinder head member having a chamber on one side of the diaphragm, said head having a passageway communicating with the chamber, a compressed air inlet port opening into said passageway, an exhaust port opening into said passageway, a valve body adapted to obstruct said ports one at a time, the exhaust port having a substantially larger area than the admission 40 port to produce a seating pressure upon the valve and means for shifting the valve from one port to the other.

2. In a pump, a cylinder, admission and exhaust valves for said cylinder, a diaphragm for operating said valves, a cylinder head member having a chamber for the diaphragm, an admission port and an exhaust port communicating with said chamber, said ports being arranged to face each other, a valve body between said ports, the area of the exhaust port being substantially greater than the area of the last said admission port, and means controlled by the level of water in the pump cylinder for moving said valve body from one port to the other.

3. In a pump, a cylinder, admission and exhaust valves for the cylinder, a diaphragm for operating the valves, a cylinder head member having a chamber for the diaphragm, an admission port and an exhaust port communicating with said chamber, said ports being arranged to face each other and having projecting valve seats, a valve body between said ports, said body having a yielding face upon each side, the area of the ex-

haust port being substantially greater than the area of the admission port and means controlled by the level of water in the cylinder for moving said valve body from one port to the other.

4. In a pump, a cylinder, admission and exhaust valves for the cylinder, a diaphragm for operating the valves, a cylinder head member having a chamber for the diaphragm, an admission port and an exhaust port communicating with said chamber, said ports being so disposed as to face each other, a valve body between said ports, the area of the exhaust port being substantially greater than the area of the admission port a stem 70 for operating said valve body, said stem passing through the cylinder head member, and a yielding diaphragm member sealing the opening around said valve stem.

5. In a pump, a valve body comprising a central passageway, an air admission port on one side of the passageway, an exhaust port on the other side of the central passageway, a plug passing through the side walls of the valve body and terminating at the central passageway, said plug member having a central cavity and radial passages communicating with the admission passageway, said plug having a port of small diameter communicating with said central cavity, a port 95 of large area opening into the central chamber and communicating with the exhaust passageway, said port having an annular seat, a valve body having a stem axially in line with both ports, said valve body having 100 a small central yielding face for covering the port of small diameter and having an annular yielding face surrounding the stem for closing the large port, and means exterior of the valve body connected to said 105 stem for shifting the valve from one port to the other.

6. In a pump, a cylinder, a compressed air inlet, admission and exhaust valves, an air motor for operating said valves, said 110 motor having a cylinder head member, said member having a central chamber, an air passageway on one side of the central chamber communicating with the air inlet, and an exhaust passageway on the other side 115 of the central chamber, said passageways terminating in ports on the interior of the chamber, said ports lying axially in line with each other, the exhaust port being annular and of a substantially greater area than the air 120 inlet port, a double faced valve member having yielding face members for closing the ports, said valve member having a stem passing axially through the exhaust port, means controlled by the level of water in 125 the pump cylinder for operating said valve member.

7. In a pump, a cylinder, a compressed air inlet, admission and exhaust valves, an air motor for operating said valves, said 130

- motor having a cylinder head member, said member having a central chamber, an air passageway on one side of the central chamber communicating with the air inlet, an 5 exhaust passageway on the other side of the central chamber, said passageways terminating in ports on the interior of the chamber, said ports lying axially in line with each other, an air inlet port being of a relatively 10 small diameter, a double faced valve member having yielding face members for covering the ports, said valve member having a stem passing axially through the exhaust port, a sleeve encircling and guiding said stem, a 15 larger sleeve forming a seat about said exhaust port, and means controlled by the level of the water in the pump cylinder for operating said valve member.
8. In a pump, a cylinder, a compressed air 20 inlet, admission and exhaust valves, an air motor for operating said valves, said motor having a cylinder head member, said member having a central chamber, an air passageway on one side of the central chamber 25 communicating with the air inlet, an exhaust passageway on the other side of the central chamber, said passageways terminating in ports on the interior of the chamber, said ports lying axially in line with each 30 other, an air inlet port being of a relatively small diameter, a double faced valve member having yielding base members for covering the ports, said valve member having a stem passing axially through the exhaust 35 port, a sleeve encircling and guiding said stem, a larger sleeve forming a seat about said exhaust port, and means controlled by the level of the water in the pump cylinder for operating said valve member, and a 40 diaphragm connected at its center to the stem of the valve member and clamped to said cylinder head member, said stem being connected to said level controlled means.
9. In a pump, a main valve for admitting 45 fluid pressure to and exhausting the same from the pump chamber, a pressure chamber having a movable element for operating said main valve, said chamber having a fluid admission passage and an exhaust passage, 50 an admission port and an exhaust port arranged substantially axially in line with each other, said ports opening into said pressure chamber, a valve having an axial bearing concentric with the exhaust port,

said valve being adapted to cover said ports alternately, and means responsive to the pump strokes for operating said valve.

10. In a pump, a main pump cylinder, main exhaust and admission valves for said pump cylinder, a pressure chamber having a movable element for controlling said main valves, said chamber having a fluid admission passage and exhaust passage, an admission port and an exhaust port arranged substantially axially in line with each other, 65 said ports opening into said pressure chamber, and a valve having an axial bearing concentric with the exhaust port for covering said ports alternately.

11. In a pump, a main pump cylinder, 70 main exhaust and admission valves for said pump cylinder, a pressure chamber having a movable element for controlling said main valves, said chamber having a fluid admission passage and exhaust passage, an admission port and an exhaust port arranged substantially axially in line with each other, 75 said ports opening into said pressure chamber, and a valve having an axial bearing concentric with the exhaust port for covering said ports alternately, a diaphragm fastened to the stem of the valve for sealing the same, and an operating arm for said stem.

12. In a pump, a main pump cylinder, 80 main valves for said cylinder, a diaphragm, a diaphragm head member having a chamber on one side of the diaphragm, an inlet port opening into said chamber, an exhaust port opening into said chamber, a valve body 90 for obstructing the ports one at a time, and means projecting through the exhaust port for moving said valve.

13. In combination, a pump having a main operating cylinder and valves, a diaphragm for operating said valves, a head member having a chamber on one side of the diaphragm, an inlet port opening into the chamber, an exhaust port opening into the chamber, a valve body for obstructing the ports one at a time, the exhaust valve having greater area than the admission valve to produce a seating pressure, and float controlled means for shifting said valve.

In witness whereof, I hereunto subscribe my name this 26th day of March, A. D. 1917.

BURTON S. AIKMAN.
